UNITED STATES PATENT OFFICE

OYSTEIN JACOBSEN, OF DAYTON, OHIO, ASSIGNOR TO THE DURIRON COMPANY, INC.,
A CORPORATION OF NEW YORK

CIRCULATING STEAM JET CONSTRUCTION

Application filed October 31, 1930. Serial No. 492,442.

The invention relates to steam jet constructions, particularly suitable for embodiment in alloys, such as high silicon iron, which are highly resistant to commercial acids abrasion and the wire-drawing action of steam, but is not limited to materials of this character. The objects of the invention are the provision of a construction in which the steam jet element is readily removable, which is of simple construction, and which is not liable to leak even after an extended period of service. One embodiment of the invention is illustrated in the accompanying drawings, wherein:

15 Figure 1 is a side elevation partly in section. Figs. 2 and 3 are detail views of the casing member, Fig. 2 being a plan view and Fig. 3 a vertical section. Figs. 4 and 5 are detail views of the replaceable jet member.

20 And Figs. 6 and 7 are detail views of one-half of the split gland member.

Referring to the drawings, 1 is the jet casing member; 2 is the jet member; 3 is the riser pipe; 4 is the gland member secured to the 25 casing member by the bolts 5; and 6 is the packing in the gland preferably in the form of asbestos rope rings.

The casing member 1 is provided with the usual transverse passage 1a tapering as 30 shown and with the socket 1b opening into such passage and having an annular shoulder 8. The jet member 2 is provided with a flange 7 which rests upon the shoulder, the shoulder being provided with a notch 9 (Fig. 3) and the flange with a lug 10 (Fig. 5) that interengage and insure that the jet member shall occupy its proper position with respect to the casing member when these parts are assembled. The engaging surfaces 35 on the flange 7 and shoulder 8 are finished smooth and true to insure sealing contact.

The riser pipe 3 has welded to one end the flange 11 and to the other end the flange 12, the latter being perforated to receive the 45 bolts by means of which the flange is clamped to the flange of the next section of pipe. The flange 11 is ground true and smooth to engage a similar ground surface on the upper face of the flange 7 and so insure a tight 50 joint at this point.

As indicated in Fig. 6, the gland member 4 is made of two similar half sections, such sections having overlapping perforated flanges with the perforations 13 to receive the clamping bolts 5. When these bolts 5 55 are tightened, the packing 6 is compressed against the flange 11 of the riser pipe forcing this flange tightly against the flange 7. The tightening of the bolts thus compresses the packing so that it performs its sealing 60 function and also insures proper sealing contact between the flanges 7 and 11. The making of the gland member in two separable parts permits the use of the riser pipe having the flanges 11 and 12 secured to its ends in a 65 permanent way thus insuring against leakage between the periphery of the pipe and the flanges.

When accurately made, the construction will operate indefinitely without leakage. 70 The only part requiring replacement in service is the jet member 2, and this replacement is readily made due to the construction as illustrated and described. This reduces the cost of replacements to a minimum, which is 75 an important consideration with expensive alloys whose fitting surfaces must be finished by grinding, which still further adds to their cost.

What I claim is:

1. In combination in a steam jet construction, a casing member having a transverse passage, and a socket opening into said passage at right angles thereto, a shoulder or ledge formed in the casing member around said socket, a jet member seated in said socket having its end turned laterally and provided with a flange engaging said shoulder, a riser pipe having a flange at its lower end also lying in the socket in opposition to the flange on the jet member, a gland member surrounding the riser pipe and extending into the upper end of the socket, packing between the lower end of the gland member and the flange on the riser pipe, and clamping means for forcing the gland member down against the packing and holding it in such position.

2. In combination in a steam jet construction, a casing member having a transverse passage, and a socket opening into said pas-

sage at right angles thereto, a shoulder or ledge formed in the casing member around said socket, a jet member seated in said socket having its end turned laterally and provided with a flange engaging said shoulder, a riser pipe having a flange at its lower end also lying in the socket in opposition to the flange on the jet member, a gland member surrounding the riser pipe and extending into the upper end of the socket, packing between the lower end of the gland member and the flange on the riser pipe, and clamping means for forcing the gland member down against the packing and holding it in such position, said shoulder and the flange on the jet member being provided with an interengaging groove and lug for fixing the position of the end of the jet member with respect to the transverse passage through the casing member.

3. In combination in a steam jet construction, a casing member having a transverse passage, and a socket opening into said passage at right angles thereto, a shoulder or ledge formed in the casing member around said socket, a jet member seated in said socket having its end turned laterally and provided with a flange engaging said shoulder, a riser pipe having a flange at its lower end also lying in the socket in opposition to the flange on the jet member, a gland member surrounding the riser pipe and extending into the upper end of the socket, packing between the lower end of the gland member and the flange on the riser pipe, and clamping means for forcing the gland member down against the packing and holding it in such position, the opposing surfaces of the shoulder in the casing and the flange on the jet member, and the opposing surfaces on the lower end of the flange on the riser pipe and on the flange on the jet member being finished smooth and true to insure sealing contacts.

In testimony whereof, I have hereunto subscribed my name this 27th day of October, 1930.

O. JACOBSEN.
